UNITED STATES PATENT OFFICE

AUGUSTE PINEAU, OF FLINT, MICHIGAN, ASSIGNOR TO A C SPARK PLUG COMPANY, OF FLINT, MICHIGAN, A COMPANY OF MICHIGAN

TIP FOR FLEXIBLE DRIVE SHAFTS

Application filed April 30, 1928. Serial No. 274,023.

This invention relates to flexible cables and particularly to a tip for the end of the cable at the point at which it is attached to the working part.

5 In prior constructions flexible cables of the multi-strand type have had their ends squared or their strands deformed in various ways so that the end of the cable would not unravel or fray at the end. There has also been placed over the cable a collar or tube which has been swedged, pressed, or deformed onto the cable and the collar or tube then severed at its mid portion to form two tips which serve as a means for attaching the 15 cable end to the working part.

The present invention is concerned with an improved tip or end on a multi-strand cable which will be an advance over prior constructions of this kind, and one which will 20 be more readily applied and capable of adaptation to its working part in a very secure relation.

The end of the flexible cable is preferably deformed to polygonal shape, or the strands 25 otherwise caused to slightly adhere so that they will not unravel. The tip portion, which is originally in the form of a stamped flat plate, is then applied to the cable end by bending and pressing the flat plate around 30 the cable and swedging, deforming or crushing it thereon so as to cause the edges of the polygonal portion of the cable to be slightly embedded in the inner periphery of the tip. This will cause a rigid adherence between the 35 tip and cable and prevent the one from turning with reference to the other.

The tip portion is provided with a pair of symmetrically arranged extensions so that when the tip is applied in its final or substantially cylindrical form, the extensions will 40 be juxtaposed or placed side by side and project away from the cable so as to form a key or feather which may be inserted in a slot on the working part to which the cable is applied. In addition, the plate edges also preferably project a short distance away from the cylindrical tip although they may be made to abut.

50 The invention is disclosed on the accompanying drawing in which:

Figure 1 shows a perspective view of the cable end with the tip applied, the parts being shown in their final or completed position.

Figure 2 is a section on the section line of 55 Figure 1, taken in the direction of the arrows.

Figure 3 is a development of the tip end, or a view of the plate before it is applied to the cable end.

Figure 4 is a sectional view showing the application of the flexible cable and tip to a speedometer drive. 60

Referring to the numbered parts on the drawing the numeral 10 indicates a flexible cable of the multi-strand type, 12 the tip portion applied to the ends thereof, while 13 indicates the individual strands of the cable. 65

In Figure 3 there is shown a development of the tip portion 12 as it appears prior to its application to the cable end. This tip 70 portion, it will be noted is a substantially flat rectangular plate and has symmetrically arranged at its sides or edges 15 and 17 the extensions or projections 14 and 16 which, when the tip 12 is applied to the cable in its 75 finished form, will form a key or feather 18 as is shown in detail in Figures 1 and 2. In its final position the plate 12 is in the form of a split collar with the extensions 14 and 16 juxtaposed and projecting away from the 80 outer periphery to form the key 18. The edges 15 and 17 also preferably project slightly outward as is shown in Figure 1 although these edges may be caused to abut and leave a substantially smooth cylindrical surface. 85

The end 20 of the cable 10 is preferably squared in any suitable way prior to the application of the tip 12. The purpose of this squaring is to obtain the sharp edges or corners 90 22 on the cable end and to prevent the individual strands from unravelling or keep the end in an unfrayed condition. As is seen from Figure 2, when the tip 12 is placed on the end of the cable and the deforming or bending operation completed, the corners 22 will be caused to embed slightly into the inner periphery 24 of the tip 12, as is shown at 26 in Figure 2. 95

Any suitable means may be used to bend 100

or deform the tip 12 around the cable 10. Preferably prior to the bending of the tip 12 around the cable end, the projections or extensions 14 and 16 are suitably bent from the plane of the tip portion 12 so that when the tip is in its final form the extensions 14 and 16 will assume the form shown in Figures 1 and 2. The plate 12 is preferably applied while cold but it may be heated if desired.

Figure 4 shows the application of the invention to a speedometer drive. In this figure the numeral 28 indicates an automobile shaft driven from the power of the engine in any suitable way. This shaft has applied thereto the worm wheel 30 which meshes with a worm 32 fixed on a shaft 34, mounted at right angles to the shaft 28 in bearings 36 and 38. The bearing 38 is preferably formed separately from the housing 40 for the shaft 28, and is screw threaded into an opening 42, the diameter of which is of a size sufficiently large to permit of the insertion of the worm wheel 32. A collar 41 is rigidly secured to the shaft 34 and abuts against the end of the bearing 38 to hold the shaft 34 and worm 32 in position.

The end 44 of the shaft 34 is hollow as shown at 46. This hollow portion has a slot or keyway 48 which is of a size adapted to receive the feather or key 18, formed by the overlapping projections 14 and 16 of the tip portion 12.

The bearing member 38 is preferably externally screw threaded to receive the nut 50 which rigidly holds in position the armor or covering 52 of the flexible cable 10. This armor or covering has its end bent over as at 54 which bent over end is confined between the end of the bearing and the nut 50.

If desired one of the projections 14 or 16 may be omitted and the remaining projection allowed to form the key 18.

In the construction as shown the key 18 is placed nearer the outer end of the tip 12; however if desired it may be placed at the inner end, or the key or feather may extend the entire length of the tip.

It is also within the scope of the invention to construct a double tip by forming a single plate having two tip portions 12. This double portion may be bent from its flat form onto the cable into its cylindrical form and then pressed, deformed or swaged onto the cable and the cable and the tip portion later severed at the mid portion of the tip, the divided two finished tip ends each provided with a feather as shown at 18. If desired the blank may first be formed to the cylindrical shape and slipped over the cable. The pressing or deforming operation will then take place.

While the invention has been shown as applied to speedometer drives it is useful in a variety of relations, such as in dentists' drills,

etc., where power is transmitted by means of a flexible cable or shaft.

I claim:

1. In a flexible cable tip, a polygonal end on said cable, a member pressed against said cable to form a tip, the corners of said polygonal end entering the member to form a rigid connection between said cable and tip member.

2. In a tip for flexible cables, a polygonal end on said cable, and a flat tip plate pressed around said polygonal end in rigid relation therewith.

3. In a tip for flexible cables having a polygonal end, a flat plate pressed around said end into substantially cylindrical form, the edges of the polygonal end embedded in the interior periphery of the plate, a plurality of extensions on said plate, said extensions bent at an angle to the cylinder to form a key or feather, and the edges of said cylinder extending away from the periphery thereof.

4. In a tip for flexible cables, a polygonal end on said cable, a flat tip plate pressed around said polygonal end in rigid relation therewith, and a key or feather formed by integral extensions or projections on said plate.

5. In a tip for flexible cables having a polygonal end, a flat plate pressed around said end into substantially cylindrical form, the edges of the polygonal end embedded in the interior periphery of the plate, a plurality of extensions on said plate, said extensions bent at an angle to the cylinder to form a key or feather, and the edges of said cylinder extending away from the periphery thereof, said extensions extending along a portion of the cylinder's length and juxtaposed in their final position.

6. In a tip for a flexible cable formed of a plurality of windings of wire wound alternately in opposite directions, comprising a flat metallic member pressed into cylindrical form around and completely surrounding the cable, and a means on the tip forming a key or feather.

7. In a tip for a flexible cable formed of a plurality of windings of wire wound alternately in opposite directions, comprising a flat metallic plate pressed into cylindrical form around the cable to form a tip.

8. In a tip for a flexible cable formed of a plurality of windings of wire wound alternately in opposite directions, comprising a flat metallic plate pressed around and completely surrounding the cable, and a key or feather on said tip formed of integral projections or extensions of said plate.

9. In a tip for a flexible cable formed of a plurality of windings of wire wound alternately in opposite directions, comprising a flat metallic plate pressed around and completely surrounding the cable, and a key or feather formed on said tip, said key or feather

formed of symmetrical integral extensions or projections formed on the plate side, said extensions or projections being juxtaposed in the final position of the tip on the cable to form the key or feather.

5 10. In a tip for flexible cables formed of a plurality of windings of wire wound alternately in opposite directions, comprising a substantially cylindrical collar surrounding the cable end and split along its entire length, and a key or feather integrally formed on said collar.

10 15. In a tip for a flexible cable formed of a plurality of windings of wire wound alternately in opposite directions, comprising a flat metallic plate pressed around the cable end into substantially cylindrical form to completely surround the cable, and a key or feather formed of an integral portion of said plate and extending axially of said tip for a portion only of its length.

15 20. In a tip for flexible cables formed of a plurality of windings of wire wound alternately in opposite directions, comprising a collar completely surrounding the cable and split in an axial direction along its entire length, and a key or feather at the split portion integral with said collar.

20 25. In a tip for flexible cables formed of a plurality of windings of wire wound alternately in opposite directions, comprising a collar split along its entire length in an axial direction and completely surrounding the cable, and a key or feather on said collar comprising a plurality of juxtaposed projections on said collar extending in an axial direction for a portion only of the length thereof.

25 30. In a tip for a flexible cable formed of a plurality of windings of wire wound alternately in opposite directions comprising a flat metallic plate pressed into substantially cylindrical form around the cable, and a key or feather on said tip and extending axially of said tip for a portion of its length and spaced from the ends thereof, said key formed from integral extensions of said plate.

30 35. In a tip for a flexible cable formed of a plurality of windings of wire wound alternately in opposite directions, comprising a substantially cylindrical collar split along the entire length thereof.

35 40. In testimony whereof I affix my signature.
50 AUGUSTE PINEAU.
